TUBING HEAD

Harry P. Wickersham, Huntington Park, and
Erwin Burns, Los Angeles, Calif.

Application May 10, 1935, Serial No. 20,842

3 Claims. (Cl. 166—14)

This invention relates to equipment for use on a well and has particular reference to a tubing head for application to the upper end of a well casing. A general object of this invention is to provide a simple, inexpensive tubing head that is operable to effectively suspend the tubing and close off the upper end of the well, when desired, during the various phases of inserting and removing the tubing and during the different phases of flowing and pumping of the well.

Another object of the invention is to provide a tubing head that includes a simple one piece body that is adapted to carry slips for suspending the tubing when the tubing is being run into or removed from the well and that is operable to carry a packer or packing assembly for suspending the tubing and sealing off about the tubing in the event that gas pressures develop in the well while running in the tubing or in the event that the well is flowing into the head when the tubing is being pulled from the well.

Another object of the invention is to provide a tubing head of the character mentioned that includes an upper section or head section to be arranged on the above mentioned body and a novel landing plug for arrangement in said head section to suspend or land the tubing and close off the upper end of the well about the tubing.

Another object of the invention is to provide a tubing head of the character mentioned in which the landing plug may be locked or held against upward movement off its seat in the head section.

Another object of the invention is to provide a tubing head that may be easily and quickly adjusted or assembled to properly and dependably suspend the tubing when the head is under well pressures as well as when there is no flow from the well.

A further object of the invention is to provide a tubing head of the character mentioned that includes a minimum number of simple sturdy inexpensive parts that form a compact unit of small dimensions.

The various objects and features of our invention will be fully understood from the following detailed description of a typical preferred form and application of the invention, throughout which description reference is made to the accompanying drawings, in which:

Fig. 1 is a vertical detailed sectional view of the head showing the tubing suspending slips in position in the body. Fig. 2 is a transverse detailed sectional view taken as indicated by line 2—2 on Fig. 1 showing the body and slips in

plan elevation. Fig. 3 is a vertical detailed sectional view illustrating the tubing landed or suspended by the packing assembly and showing the head section in position on the body and carrying a gate valve. Fig. 4 is a fragmentary horizontal detailed sectional view taken as indicated by line 4—4 on Fig. 3. Fig. 5 is a vertical detailed sectional view showing the tubing suspended from the landing plug and illustrating a gate valve connected with the upper section or head section. Fig. 6 is a view similar to Fig. 5 taken in a vertical plane substantially 90° to the plane of sectioning of Fig. 5, showing a gland or packing means on the head section sealing about a sucker rod extending into the tubing and Fig. 7 is a side elevation of a tool for handling the hold down ring.

The present invention includes, generally, a tubing head body 10 adapted to be arranged on the upper end of a well casing C, slips 11 for arrangement in the body 10 to suspend a string of tubing T as it is being run into or pulled from the well, a packer or packing assembly 12 adapted to be arranged in the body 10 for suspending and packing about the string of tubing T, a head section or upper section 13 adapted to be arranged on the body 10 and a landing plug 14 adapted to be seated in the section 13 for landing or suspending the tubing T from its upper end.

The tubing head body 10 is adapted to be applied to the upper end of the well casing C and is formed to receive and carry the slips 11, the packing assembly 12 and the upper section 13. The body 10 is preferably a simple one piece member of relatively small vertical dimensions. The body 10 is tubular having a central longitudinal opening 15 which is concentric with or coaxial with the opening of the well casing C. The body opening 15 is preferably as large in diameter as the opening of the casing C. The body 10 may be attached to the casing C in any suitable manner. In the particular case illustrated in the drawings the lower portion of the body 10 is internally threaded to be directly screwed on the upper end portion of the casing C. In accordance with the invention a projecting radial flange 16 is provided on the upper end of the body 10. The flange 16 may be continuous or annular and may be provided with spaced vertical openings 17.

The upper portion of the body opening 15 is flared upwardly and outwardly or provided with an inclined seat 18 to carry the slips 11 and the packing assembly 12. Where the tubing T to be

55

handled is of large diameter the upper portion of the body opening 15 may be increased in diameter so that the seat 18 is proportioned to carry slips and a packing assembly for handling the 5 large tubing. One or more spaced ports 19 extend through the wall of the body 10 for the discharge of fluid from the well and for passing fluid in the well to kill well pressures, etc. In the particular embodiment of the invention illustrated 10 in the drawings there are two ports 19 provided in the body at diametrically opposite points. The inner ends of the ports 19 communicate with the body opening 15 at points between the upper end of the casing C and the active portion of the seat 15 18. The ports 19 are inclined or curved upwardly and outwardly to have their outer ends adjacent the upper end of the body 10. This curving or inclination of the ports 19 allows the body 10 to be of small dimensions and yet bring the outer 20 ends of the ports 19 in convenient locations. The body wall may be thickened at or around the ports 19 as at 20. Conduits or pipes 21 may be threaded into the outer ends of the ports 19 to conduct fluid to and from the head. 25 The slips 11 are adapted to be arranged in the body 10 on its seat 18 to grip and suspend the tubing T when the string of tubing is being assembled and run into the well. The slips 11 are arcuate or segmental members adapted to form 30 an annular assembly. The slips 11 may be provided in sets of three or four each. In the particular case illustrated there are three slips 11 each being of substantially 120° extent. The outer surfaces 22 of the slips 11 are inclined 35 downwardly and inwardly and are curved to evenly cooperate with the body seat 18. The inner sides of the slips 11 are substantially cylindrically curved or cylindrically concaved and are provided with upwardly and inwardly facing 40 teeth 23 for gripping and holding the tubing T. The tops or upper ends of the slips 11 may be flat and horizontal. The slips 11 are preferably proportioned so that their upper ends are substantially flush with the upper end of the body 45 10 when they are in position on the seat 18 and gripping the tubing T. If desired the slips 11 may be socketed or provided with openings 24 to be light in weight, in which case their inner and outer portions are connected by webs 25. The 50 lower outer corners of the slips 11 may be cut away or bevelled as at 26 to lighten the slips and leave the ports 19 exposed. During the running of the tubing T into the well the slips 11 may be assembled in the body 10 to support the string 55 of tubing while a section of tubing is being connected with its upper end.

The packer or packing assembly 12 is intended to be arranged on the seat 18 to suspend the tubing T and seal off the upper end of the body 10 in 60 the event that pressures develop in the well when running in or withdrawing the string of tubing T. The packing assembly 12 is also adapted to be employed to suspend the tubing T and seal off the upper end of the body 10 when the well is 65 flowing into the head while the tubing T is being pulled from the well. In the particular form of the invention disclosed in the drawings the packing assembly 12 comprises two sections A and B each including a body 27 of packing, a collar section 28 on the upper end of the packing body 27, and a collar section 29 at the lower end of the packing body 27. The bodies of packing 27 are arcuate being substantially 180° in circumferential extent and have inclined outer surfaces for 70 sealing with the seat 18. The inner sides of the

bodies 27 of packing are cylindrically concaved to form an opening 30 for receiving the tubing T. The packing bodies 27 are proportioned to tightly seal with the seat 18 and the tubing T when compressed. The collar sections 28 and 29 cover the upper and lower ends, respectively, of the bodies 27 of packing. Bolts or screws 31 extend through openings in the collar sections 28 and the bodies 27 of packing and thread into openings in the lower collar sections 29 to hold the parts in the proper assembled relation. The sections A and B of the packing assembly are preferably hinged together as at 9 so that they may be readily handled as a unit. When the packing assembly 12 is arranged on the seat 18 as illustrated in Figs. 15 3 and 4 of the drawings, a collar or coupling 32 on the tubing T may bear downwardly on the upper collar sections 28 to suspend the string of tubing T and to compress the packing 27 so that it effectively seals with the seat 18 and the tubing 20 T. The packing assembly 12 is proportioned so that its lower end leaves the ports 18 uncovered or open to allow the escape of fluid from the well and to permit mud or liquid to be passed into the well to kill the well pressures. 25

The head section or upper body section 13 is adapted to be applied to the body 10 when the tubing T is to be landed or suspended by means of the landing plug 14, as illustrated in Figs. 5 and 6 of the drawings. The section 13 is also adapted 30 to be applied to the upper end of the body 10 when the tubing T is suspended and packed about by the packing assembly 12, as shown in Figs. 3 and 4, and fluid is flowing into the head and through the tubing. In accordance with the invention the section 13 has an outwardly projecting flange 33 at its lower end adapted to oppose or seat on the body flange 16. Bolts 34 are passed through the openings 17 and openings in the flange 33 to attach the section 13 to the body 10. 40 The invention provides means for sealing between the body 10 and the section 13. An annular groove 35 is provided in the upper face of the body 10 and carries a gasket or packing 36. An annular projection or ridge 37 is provided on the lower end of the section 13 to fit in the groove 35 and compress the packing 36. The packing 36 sealing with the walls of the groove 35 and with the ridge 37 forms a tight fluid seal between the body 10 and the section 13. 45

The upper portion 38 of the section 13 is of reduced diameter and is preferably cylindrical. The wall of the section 13 arches or curves upwardly and inwardly from the flange 33 to the reduced portion 38. The upper reduced portion 38 of the section 13 is provided with an internal seat 39. The seat 39 has a downwardly and inwardly tapered or inclined wall to receive the landing plug 14. The tubing T is adapted to enter or extend through the seat 39 with considerable clearance. The exterior of the reduced portion 38 is externally screw threaded so that a gate valve V may be threaded onto it as illustrated in Figs. 3 and 5 of the drawings and so that a gland may be threaded to it as shown in Fig. 6 of the drawings. 55

The landing plug 14 is provided to suspend the string of tubing T from its upper end when the string has been set or anchored in the well. The plug 14 is adapted to be arranged on the seat 39 to carry or suspend the tubing T and to form a 70 closure or packing member sealing between the tubing and the seat. The plug 14 is a tubular member having a central longitudinal opening 40. The lower portion of the plug opening 40 is threaded to receive the threaded upper end of the 75

tubing T as shown in Figs. 5 and 6. The upper portion of the opening 40 may be threaded to receive the end portion of a pipe or fitting for handling the plug or for carrying fluid from the tubing. The exterior of the plug 14 is tapered to evenly engage the seat 39. In accordance with the invention means is provided for sealing or packing between the plug 14 and the seat 39. Spaced annular grooves 41 are provided in the exterior of the plug 14 and carry packing 42 which is adapted to seal with the seat 39.

It is preferred to provide means for holding the landing plug 14 against upward movement to prevent it from being raised from the seat 39 in the event that high pressures develop in the well. The upper portion of the plug 14 is of reduced external diameter to have an upwardly facing annular shoulder 43. A threaded opening or socket 60 is provided in the upper end of the portion 38 and its lower wall forms an upwardly facing shoulder 61. A hold down ring 44 is threaded into the socket 60 to bear downwardly on the shoulder 43 and hold the plug 14 on the seat 39. A sealing gasket 62 is engaged by the lower end of the ring 44 to seal with the shoulder 43, the shoulder 61 and the lower end of the ring. The ring 44 may have a crown or portion projecting above the upper end of the section 13 provided with notches 45 to facilitate the turning and threading of the ring. The invention provides a novel means for handling the ring 44. The notches 45 are substantially T shaped having oppositely extending lateral branches 66 at their inner ends. A tool 66 is provided for handling and turning the ring 44. The tool 66 is preferably tubular and has substantially T shaped lugs 67 on its lower end. The lugs 67 are adapted to enter the mouths of the notches and their arms 68 are adapted to cooperate with the branches 66 whereby the ring 44 may be turned in either direction and carried by the tool 66.

When the tubing T is landed in the head by the plug 14 and the well is flowing through the tubing T the gate valve V is preferably provided on the head to control the flow and to carry the Christmas tree assembly (not shown). In most instances it may be desirable to directly thread the lower end of the valve V on the reduced upper portion 38 of the section 13. It is to be understood that adapters or other parts may be threaded on the portion 38 if desired to connect with a gate valve, or the like. In accordance with the invention the plug 14, the ring 44 and the tool 66 are proportioned so that they may be passed through the valve V whereby the plug 14 may be screwed and locked in place and removed from the head without disturbing or detaching the valve V. When the gate G of the valve V is in its open position the tool 66 may be passed through the passage 70 and the seat of the valve V to unscrew the ring 44 whereupon the ring may be withdrawn through the valve on the tool. A pipe or like object may then be inserted through the valve V and threaded in the upper end of the plug 14 for the purpose of removing the plug 14 through the valve V. The plug 14 and the ring 44 may be inserted through the valve V and arranged in position in a similar manner if desired.

When the well is being pumped a pump operating sucker rod 50 extends downwardly through the string of tubing T. The rod 50 passes through the landing plug 14 and a gland 51 is threaded on the upper portion 38 of the section 13 to carry packing 52 for sealing about the rod. A follower 75 53 is threaded in the upper end of the gland 51

to compress the packing 52. A fluid discharge opening may be provided in the gland 51 to allow the discharge of fluid pumped.

It is believed that the features and uses of the invention will be readily apparent from the foregoing detailed description. The head involves an assembly of parts that may be easily and quickly adjusted and assembled to suspend the tubing T during the insertion and removal of the tubing and during the various phases of flowing and pumping of the well. The simple head 10 is formed to properly carry the slips 11 and the packing assembly 12 and is adapted to directly carry the upper section 13. The slips 11 are easily assembled on the seat 18 to suspend the tubing T during the running of the tubing into or out of the well. In the event that well pressures develop when the tubing is being run into or removed from the well the packing assembly 12 may be quickly inserted in the body 10 to suspend the tubing and seal off the upper end of the body. The upper section 13 may be easily attached to the body 10 when the packing assembly 12 is in the body as shown in Fig. 3 and may be secured to the body to carry the landing plug 14 when the tubing T is to be finally landed. The plug 14 is a simple sturdy part which dependably suspends the tubing T and forms a tight seal with the seat 39. The tubing head of the present invention is inexpensive to manufacture and occupies a minimum space at the upper end of the well.

Having described only a typical preferred form and application of our invention, we do not wish to be limited or restricted to the specific details set forth, but wish to reserve to ourselves any variations or modifications that may appear to those skilled in the art or fall within the scope of the following claims:

Having described our invention, we claim:

1. In combination a tubing head body applied to the upper end of a well casing, said body being formed with a central unobstructed opening, a section applied to the upper end of said body and lying in a plane substantially entirely above the end face of said body and forming a sealed closure for the body, a tubular extension forming a part of and projecting upwardly from said upper section and being formed with a tapered seat therethrough, an internally threaded tapered plug adapted to fit within said seat and to provide a threaded connection for the upper end of a tubing, and a ring nut threaded into the mouth of the tubular extension of the upper member and engaging the tapered plug to hold the same on its seat.

2. In combination a tubing head body applied to the upper end of a well casing, said body being formed with a central unobstructed opening, a section applied to the upper end of said body and lying in a plane substantially entirely above the end face of said body and forming a sealed closure for the body, a tubular extension forming a part of and projecting upwardly from said upper section and being formed with a tapered seat therethrough, an internally threaded tapered plug adapted to fit within said seat and to provide a threaded connection for the upper end of a tubing, the mouth of the tubular extension of the upper member being counterbored and threaded, said counterbore terminating with a square shoulder, the upper end of the tapered plug being reduced in diameter with a square shoulder lying substantially in the plane of the square shoulder of the counterbore, packing

means disposed upon said shoulders and sealing the joint therebetween, and a ring nut threaded into said counterbore and sealing the space occurring between the reduced portion of the tapered plug and the counterbore whereby packing pressure will be exerted against the packing means.

3. In combination with a well casing, a tubing head adapted to be applied to the upper end 10 of said casing, comprising a body fitted to said casing and having a central passageway therethrough substantially corresponding in diameter with the mouth of the well casing and centrally aligned therewith, and having upwardly and outwardly tapering walls, a horizontal face upon the upper end thereof formed with a circular packing groove, ports formed in the wall of said body member and extending radially thereof to accommodate a flow of fluid from the casing, an 15 upper section mounted upon said body section and having an annular lip extending into the

groove in the body member to form a seal therewith, means clamping the two sections together, an upper passageway in said upper section through which a tubing string may extend, and a packer assembly adapted to seat within the tapered opening of the body member, said packer assembly comprising a yieldable central packing element having a central opening to receive the tubing string and split radially at one side so that it may be sprung around the tubing string 10 and the upper and lower plates between which the packing element is positioned, said plates having a central opening to accommodate the drill string, said plates being secured together through the packing, and each of said plates being formed in two semi-circular halves, which halves are hinged together on the side opposite to the split in the packing element.

HARRY P. WICKERSHAM. 20
ERWIN BURNS.
